VACUUM BOTTLE JACKET

Howard W. Phillips, Nashville, Tenn., assignor to Aladdin Industries Incorporated, Chicago, Ill., a corporation of Illinois

Filed Oct. 8, 1964, Ser. No. 82,092

Term of patent 14 years

(Cl. D58—8)

FIG. 2.

FIG. 4

FIG. 1.

FIG. 3.

FIG. 1 is an elevational view of a vacuum bottle jacket, showing my new design;

FIG. 2 is a top plan view thereof;

FIG. 3 is a fragmentary elevational view of the bottom thereof on an enlarged scale; and

FIG. 4 is a cross-sectional view taken along line 4—4 in FIG. 1.

The broken line portions are shown for illustrative purposes only.

I claim:

The ornamental design for a vacuum bottle jacket, substantially as shown and described.
